UNITED STATES PATENT OFFICE.

GABRIELLE DE NOTTBECK, OF NEW YORK, N. Y.

DESIGN FOR AN INSECT-CASE.

Specification forming part of Design No. **7,180**, dated February 17, 1874; application filed January 17, 1874.
[Term of Patent 3½ years.]

To all whom it may concern:

Be it known that I, GABRIELLE DE NOTTBECK, of the city, county, and State of New York, have invented a new and original Design for Insect-Case, of which the following is a specification;

The accompanying drawing represents an insect-case in perspective view contrived according to my new design.

The design relates to a rectangular case or box, *b*, having a convex transparent top, *a*.

The case forms an ornamental cage or prison for insects. The accompanying drawing shows the case in perspective.

What I claim is—

The design for an insect-case formed by the box *b* and the convex top *a*, as shown and described.

GABRIELLE DE NOTTBECK.
